STABILIZATION OF ANIMAL AND
VEGETABLE FATS AND OILS

James K. Hunt and George H. Latham, Wilmington, Del., assignors to E. I. du Pont de Nemours & Company, Wilmington, Del., a corporation of Delaware

No Drawing. Application February 15, 1935,
Serial No. 6,644

20 Claims. (Cl. 87—9)

This invention relates to the stabilization of animal and vegetable fats and oils and particularly unsaturated fatty glycerides.

It is well known that animal and vegetable fats and oils tend to become rancid and discolored on storage. It is not definitely known just what causes this deterioration. It has been suggested that this deterioration is due to oxidation or to the action of micro-organisms or to hydrolytic reactions caused by enzymes or due to minute amounts of impurities. Such deterioration is highly objectionable and renders the fats and oils unfit for many uses. Many attempts have been made to overcome this deterioration. It has been proposed to add various substances to the fats and oils to inhibit or retard such deterioration. Among such substances are certain aromatic amino compounds. These substances have not proved to be entirely satisfactory for the reason that the compounds are too expensive, too volatile, discolor the fats and oils, are toxic, or give the fats and oils an objectionable odor or taste.

An object of our invention is to provide a new class of compounds to be incorporated in animal and vegetable fats and oils which will retard or inhibit deterioration of the fats and oils and will not have the disadvantageous properties of prior compounds employed for this purpose. A further object is to provide such compounds which will be particularly suitable for use in edible fats and oils. Other objects are to provide new compositions of matter and to advance the art. Still other objects will appear hereinafter.

These objects may be accomplished in accordance with our invention which comprises incorporating in animal and vegetable fats and oils small amounts of sugar amines. By a sugar amine, we mean an amine of a reducing sugar containing a carbon chain of at least five carbon atoms. These amines may be employed as the free bases or as the salts of aliphatic acids, particularly the long chain fatty acids. The free bases may be represented by the formula

wherein R represents a carbon atom of a sugar nucleus containing a carbon chain of at least

five carbon atoms and each of R₁ and R₂ represents hydrogen or a carbon atom of an organic group. The sugar amines may also be defined as amino alcohols in which the alcohol radical is a normal open-chain radical containing at least five carbon atoms and having a hydroxyl group attached to each carbon other than the one attached to the nitrogen. The sugar amines may be employed as their aliphatic ethers or esters, that is, the hydrogens of one or more of the OH groups may be replaced by alkyl, hydroxy alkyl or acyl radicals, such as ethyl, hydroxy ethyl or acetyl radicals. However, such ether and ester type compounds are generally less effective and hence are less desirable.

Some of the simple primary sugar amines are known and the methods of preparing them are also known. Some of the simple secondary and tertiary amines and the methods of preparing them are known. Some of the secondary and tertiary amines and methods for preparing them are disclosed in the copending applications of P. L. Salzberg and R. B. Flint, Serial Nos. 635,045; 635,046 and 635,047 filed September 27, 1932, issued as Patents 2,016,962, 1,994,467 and 2,016,963, respectively.

In general, the method of preparing the secondary and tertiary amines comprises reacting the sugar with a primary or secondary amine and hydrogen at superatmospheric pressures and temperatures in the presence of hydrogenating catalyst. For example, methyl glucamine may be prepared by placing 80 parts of methyl amine, 100 parts of commercial glucose and 80 parts of water into a pressure vessel with 9 parts of a reduced nickel catalyst comprising reduced nickel supported on kieselguhr, the reduced nickel comprising 20% of the catalyst. Hydrogen may be then introduced to a pressure of 2000 lbs. and the ingredients agitated vigorously during the heating. Hydrogen absorption begins at 100° C. and is complete in fifteen minutes. The maximum temperature during this time should be about 120° C. The product may be separated from the catalyst by filtration, and the filtrate evaporated until crystallization occurs. Methyl glucamine may be recrystallized from this residue as a white solid melting at 127–128° C. The reaction taking place may be represented as follows:

Under certain conditions sugar amines may be alkylated by reacting with an alkyl halide or an alkyl sulfate at room temperature or slightly above room temperature in order to form secondary and tertiary amines such as dodecyl glucamine and dodecyl methyl glucamine. However, this process is generally less satisfactory for the preparation of pure monoalkyl sugar amines than the one given above.

Other amines which may be employed for preparing secondary and tertiary sugar amines coming within our invention are monoethyl amine, diethyl amine, monopropyl amine, dipropyl amine, monobutyl amine, dibutyl amine and mono- and di-amines of the higher saturated aliphatic type such as dodecyl and octadecyl amine, phenylethyl amine, mono- and di-benzyl amine or other aralkyl amines, and aryl amines such as aniline, toluidine, and naphthylamine and mixed amines such as phenyl ethyl amine, methyl benzylamine and the like. Thus R_1 and R_2 in the formulae may be methyl, ethyl, isopropyl, butyl, amyl, isoamyl, octyl, dodecyl, cetyl, cyclohexyl, cyclohexanol, phenyl, phenylol, naphthyl, and the like.

Among the sugars which may be employed to produce amines coming within our invention are: glucose, fructose, xylose, ribose, lyxose, lactose, arabinose, mannose, rhamnose, galactose, sorbose, sorbinose, gulose, and talose.

The sugar nucleus may be alkylated by the usual methods of preparing ethers such as by treating with an alkyl halide or alkyl sulfate such as ethyl chloride or diethyl sulfate to replace the hydrogens of one or more of the OH groups by the alkyl group. The degree of alkylation will depend primarily upon the proportions employed.

The sugar nucleus may also be acylated. The method of preparing such compounds comprises treating the sugar or sugar amine with an acid halide or anhydride such as acetyl chloride or acetic anhydride under anhydrous conditions and at superatmospheric temperatures. The resulting compounds are esters in which the hydrogens of one or more of the OH groups are replaced by the acid radical. The degree of acylation will depend primarily upon the proportions of the ingredients employed.

The hydrogens of one or more of the OH groups of the sugar radical may be replaced by hydroxy alkyl groups by reacting the sugar or the sugar amine with an alkylene oxide such as ethylene oxide in the cold. For example, 50 parts of glucamine may be dissolved in 50 parts of water and cooled to 20° C. 17.2 parts of ethylene oxide may then be added. The reaction takes place without heating. The formula of the reaction product is not definitely known but it is believed that the reaction probably takes place as follows:

The salts of the sugar amine bases may be prepared by melting the acid and the base together or, where either the acid or the base or both are liquids, merely by mixing.

In general, we have found the secondary amines and their salts to be most effective. This is particularly true of those compounds in which each group is an organic group devoid of acidic substituents. Also, the sugar amines containing long chain aliphatic hydrocarbon groups are

more soluble in the oils and fats and less soluble in water than the amines which do not contain these groups. Further, the aliphatic acid salts, particularly those of long chain fatty acids are generally more soluble in the oils and fats than the free bases. By the term "long chain", as employed herein and in the claims, we mean carbon chains of at least 8 carbon atoms.

The proportion of amine employed in any oil will depend upon the particular oil, the particular amine and the degree of stabilization desired. We have found that from about 0.1% to 1.0% is satisfactory in most cases. The amounts to be used in practice may vary from about 0.001% up to 2% or more. It will generally be preferred to employ amounts of not more than about 0.1% in edible fats and oils.

Some of the compounds which we have found to be particularly satisfactory for our purpose are as follows:

In order to more clearly illustrate our invention the preferred modes of carrying the same into effect, and the advantageous results to be obtained thereby, the following examples are given:

Example 1

A representative sample of purified cottonseed oil was obtained. Half of it was employed as a control or blank and to the other half was added 1% of methyl glucamine on the basis of the oil. The mixture was well shaken and allowed to stand over night to insure a saturated solution, as the compound is not soluble in cottonseed oil to the extent of 1%. Pieces of quantitative

filter paper 5" x 2" were saturated with the well shaken solution and the excess oil absorbed between clean white blotting paper. The impregnated filter papers were placed in carefully cleaned, glass-stoppered bottles and stored at 65° C. in the dark, and in duplicate experiments, at room temperatures (25-30° C.) in diffused light. The control or blank tests were similarly carried out on the control portion of oil set aside as indicated above. All tests were run in

duplicate. The bottles were examined daily for rancid odor and for any discoloration of the oil impregnated filter paper. Results were as follows:

Agent	Days for rancidity to develop at		Discoloration of oil
	65° C.	Room temp.	
None (untreated oil)-----	5	22	None.
Methyl glucamine-----	77	37	None.

Example 2

15 To a portion of melted lard, 1% of methyl glucamine was added and stirred in at about 100° C. A second portion of the same lot of lard (containing no stabilizer) was used as a blank or control. After cooling, rancidity tests were run with these portions of lard at 65° C. as in Example 1. The untreated lard became rancid in two days, whereas the treated lard required seven days to become rancid.

Example 3

A sample of cold pressed castor oil was divided into two portions. To one was added 0.5% of methylglucamine. The other portion was used as a blank or control. Both portions of oil were heated to 100° C., as this aided in dissolving the methylglucamine in the oil to which it was added. After cooling, filter papers were impregnated with the oils, and rancidity tests were made at 65° C. as in Example 1. The results are given in the following table:

Agent	Days for rancidity to develop at 65° C.		Discoloration of oil
	65° C.	Room temperature	
None (untreated oil)-----	53	Definitely yellow.	None.
Methylglucamine-----	146	None.	None.

45 Note that, in this case, the inhibitor prevented the discoloration on aging that normally occurs in castor oil.

Example 4

50 A sample of air-blown cottonseed oil was divided into two portions. One portion was employed as a blank or control while to the other was added 1% of methylglucamine, based on the oil. Rancidity tests were run at 65° C. as in Example 1. The untreated oil became rancid in one day. The treated oil did not become rancid in 33 days.

Example 5

60 A portion of China-wood oil was heated to 420° F., requiring 1 hour, held at that temperature for one hour and then cooled. To this oil was added 0.03% of cobalt as cobalt linoleate. Such a composition skins over in air very badly within 24 hours. The mixture was divided into 65 two portions. One was employed as a blank or control, and to the other was added 1% of glucamine. The two portions were placed side by side in open tin cans in a room at about 25° C. The untreated control skinned badly in 24 hours, 70 while the treated portion was unskinned after 2 weeks and was only slightly darker in color than the untreated portion. It may be noted that, when such oil skins over, the body of the oil is protected from the atmosphere by the film or 75 skin.

Example 6

Refined cottonseed oil containing 1% of glucamine was tested for rancidity at 65° C., as in Example 1 along with a portion of untreated cottonseed oil of the same lot. The untreated oil became rancid in six days, whereas the treated oil required ten days to develop rancidity. Neither of the oils discolored.

Example 7

10 Refined cottonseed oil containing 1% of ethanol glucamine was tested as in Example 1. Results:

Agent	Days for rancidity to develop		Discoloration
	65° C.	Room temperature	
None (untreated oil)-----	4	8	None.
Ethanolglucamine-----	7	15	None.

Example 8

15 Refined cottonseed oil containing 1% of dodecyl methyl glucamine was tested as in Example 1. The results are given in the following table:

Agent	Time for rancidity to develop		Discoloration of oil
	65° C.	Room temperature	
None (untreated oil)-----	4	8	None
Dodecyl methylglucamine-----	7	11	None

Example 9

20 Acetylated methyl glucamine was prepared by placing 312 parts (3 mols) of acetic anhydride and 31 parts of anhydrous sodium acetate in a reaction vessel and heating to reflux temperature. 75 parts of methylglucamine ($\frac{5}{12}$ of a mole) was added in small portions. The boiling 45 was continued for 25 minutes, the mixture cooled, 50 poured into 1200 parts of ice water and was then neutralized with a 40% solution of potassium hydroxide. The precipitate, which settled out, was filtered off and recrystallized from 150 parts of hot water. The melting point of the material was 114-115° C. Analysis indicated that the formula of the material was one of the following:

55 1% of this material was incorporated in refined cottonseed oil and tested at room temperature as in Example 1. The untreated oil developed rancidity in eight days, whereas the treated oil required twelve days to develop this rancidity. 60 Neither oil discolors.

Example 10

70 A pie crust was prepared consisting of approximately 50% fat containing 1% methylglucamine. A check or control pie crust, containing the same amount of the same fat but without a stabilizer, was also prepared. Each pie crust was divided into portions, one of which was crushed and the other remained uncrushed. All 75

portions of the pie crust were stored in the light at room temperature. The pie crust used as a check or control was shown to be definitely more susceptible to rancidity than was the pie crust containing the methyl glucamine.

Example 11

A portion of lard was treated with 0.1% methyl glucamine, based on the weight of lard. Another 10 portion of lard was untreated. Air was passed through the two portions at the same rate at 100° C. The time required for each sample to reach a peroxide value of 20 milli-equivalents of peroxide per 1000 g. of lard was determined (this 15 peroxide value having been previously found to indicate a rancid state of the lard). It was found that 7 hours was required for the control portion of lard to reach a peroxide value of 20, while the time required for the lard containing 0.1% 20 methylglucamine was 54 hours. These tests were run according to the technique described in "Oil & Soap", June, 1933, p. 105-9.

Example 12

25 Samples of refined cottonseed oil, containing 1%, on the basis of the oil, of the following sugar amines, were tested for rancidity at 65° C. as in Example 1 with results indicated below:

30	Antioxidant	Hours for rancidity to develop at 65° C.	Discoloration of oil
	None (untreated oil)		None.
	Dodecyl glucamine	176	None.
35	Amyl glucamine	382	None.
	Butyl xylamine	360	None.
	Methyl fructamine	528	None.
	Methyl galactamine	494	None.
	Methyl glucamine stearate	260	None.
		528	None.

40 The above examples are merely illustrative of some of the compounds of our invention and some of the compositions in which they may be employed. Our compounds may be employed to inhibit development of rancidity in other animal and vegetable fats and oils such as linseed oil, China-wood oil, other esters of linoleic, linolenic, and eleostearic acids, cottonseed oil, castor oil, olive oil, rape seed oil, cod liver oil and other fish oils, coconut oil, palm oil, corn oil, peanut oil, sesame oil, neat'sfoot oil, butter fat, lard, beef tallow, and hydrogenated oils and fats such as "Crisco" and "Snowdrift". Our compounds may also be employed in oils and fats which have been previously subjected to various treatments such as blowing with air at more or less elevated temperatures or to simple heat treatments. Moreover, such raw or processed oils are often used as ingredients in various compositions such as textile lubricants, clear lacquers for coating paper, and the like. Furthermore, the edible oils are frequently employed in the preparation of pastries and other bakery products, potato chips, mayonnaise, salad oils and the like. Our compounds will be found to be effective for inhibiting rancidity and discoloration of the oils and fats in these various types of compositions.

45 Our compounds have been brought into intimate contact with the skin without having any harmful effect thereon. Small amounts of the materials themselves have been eaten by human beings without any harmful effects being detected. Accordingly, it appears that our compounds are harmless or non-toxic to human beings. They are derived from sugars which are in themselves foodstuffs. They do not cause objectionable taste or odor or discoloration of the

5 fats and oils in which they are incorporated when employed in the proportions indicated. They have low volatility so that they have little tendency to volatilize during heating of the fats such as occurs during cooking or in deepfat frying operations. Some of them are more soluble in the fats and oils than in water. For all of the above reasons, our compounds are particularly adapted for use in edible fats and oils. This is an important feature of our invention.

10 Other sugar amines falling within our invention are:

	I	Primary amines	15
Fructamine		Rhamnamine	
Xylamine		Galactamine	
Ribamine		Sorbinamine	
Lyxamine		Sorbamine	
Lactamine		Gulamine	
Arabinamine		Talamine	
Mannamine			20

	II	Secondary amines	20
Ethyl glucamine		Methyl xylamine	
Isopropyl glucamine		Butyl xylamine	
N-butyl glucamine		Benzyl xylamine	
Isobutyl glucamine		Ethyl galactamine	
Octyl glucamine		Methyl mannamine	
Benzyl glucamine		Amyl arabinamine	
Cyclohexyl glucamine		Diglucamine	
Cyclohexanol glucamine		Dixylamine	
Phenyl glucamine		Diisooctylamine	
Hydroxyphenyl glucamine		Reaction product of glucamine and xylose	30
Naphthyl glucamines			

	III	Tertiary amines	
Dimethyl glucamine		Octyl methyl glucamine	
Difurfuryl glucamine		Didodecyl xylamine	35
Dimethyl fructamine			

	IV	Salts	
Glucamine stearate		Methyl glucamine oleate	
Glucamine oleate		Xylamine stearate	

50 As has been pointed out heretofore, our amines may be employed as the free bases or as the salts of aliphatic acids and particularly of the long chain or fatty acids. Among the fatty acids which may be employed to form the salts of these amine bases, may be mentioned:

Lauric acid	Linolic acid
Hydroxy stearic acid	Linolenic acid
Coconut oil acids	Linseed oil acids
Elaidic acid	Behenic acid
Erucic acid	Behenolic acid
Brassicidic acid	Ricinoleic acid
China-wood oil acids	Castor oil acids
Eleostearic acid	Abietic acid and the like
Stearolic acid	

55 Some of the free amines of our invention are oil and fat soluble and substantially insoluble in water. This is particularly true of the sugar amines containing long chain hydrocarbon groups. These amines may be incorporated in the fats and oils merely by mixing. In stabilizing oils or fats in which the sugar amines are only slightly soluble, the sugar amine to be employed should be added and well stirred into the oil and the mixture allowed to stand until a saturated solution is obtained when the clear oil or fat can be decanted off or filtered, or the undissolved amine can be allowed to remain in the oil or fat or composition containing it, as a dispersion. In some cases the sugar amines will dissolve more readily in hot oil or fat. The least soluble can generally be rendered soluble by employing them as their salts or soaps, particularly, 60 of the fatty acids.

65 While we have disclosed the preferred form of our invention and the preferred modes of carrying the same into effect, and indicated some of the variations and modifications that may be made 70

therein, it will be readily apparent to those skilled in the art that many other modifications and variations may be made therein without departing from the spirit of our invention. Accordingly, the scope of our invention is to be limited solely by the appended claims, construed as broadly as is permissible in view of the prior art.

We claim:

1. Compositions comprising animal and vegetable fats and oils having incorporated therein a sugar amine compound in which the sugar radical contains at least 5 carbon atoms one carbon atom being singly bonded to the amino nitrogen and to carbon and hydrogen solely, in an amount sufficient to inhibit deterioration of the fats and oils on storage.

2. Compositions comprising animal and vegetable fats and oils having incorporated therein a secondary sugar amine compound in which the sugar radical contains at least 5 carbon atoms one carbon atom being singly bonded to the amino nitrogen and to carbon and hydrogen solely, in an amount sufficient to inhibit deterioration of the fats and oils on storage.

25 3. Compositions comprising animal and vegetable fats and oils having incorporated therein a secondary sugar amine compound in which the sugar radical contains at least 5 carbon atoms one carbon atom being singly bonded to the amino nitrogen and to carbon and hydrogen solely and having one amino hydrogen replaced by an aliphatic group, in an amount sufficient to inhibit deterioration of the fats and oils on storage.

4. Compositions comprising animal and vegetable fats and oils having incorporated therein an amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

45 5. Compositions comprising animal and vegetable fats and oils having incorporated therein a secondary amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

6. Compositions comprising animal and vegetable fats and oils having incorporated therein an amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen and in which at least one amino hydrogen has been replaced by a hydrocarbon radical, in an amount sufficient to inhibit deterioration of the fats and oils on storage.

7. Compositions comprising animal and vegetable fats and oils having incorporated therein a secondary amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen and in which the other substituent of the secondary amino group is a hydrocarbon group, in an amount suffi-

cient to inhibit deterioration of the fats and oils on storage.

8. Compositions comprising animal and vegetable fats and oils having incorporated therein an N-aliphatic substituted amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

9. Compositions comprising animal and vegetable fats and oils having incorporated therein a mono N-aliphatic substituted amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

10. Compositions comprising animal and vegetable fats and oils having incorporated therein a mono N-alkyl substituted amino alcohol compound in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

11. Compositions comprising animal and vegetable fats and oils having incorporated therein an amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

12. Compositions comprising animal and vegetable fats and oils having incorporated therein a secondary amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

13. Compositions comprising animal and vegetable fats and oils having incorporated therein a mono N-aliphatic substituted amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

14. Compositions comprising animal and vegetable fats and oils having incorporated therein a mono N-alkyl substituted amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

15. Compositions comprising animal and vegetable fats and oils having incorporated therein

5 a salt of an aliphatic acid and an amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

16. Compositions comprising animal and vegetable fats and oils having incorporated therein 10 a salt of a long chain aliphatic acid and an amino alcohol in which the alcohol radical is an open-chain radical containing at least 5 carbon atoms one carbon atom being singly bonded to the amino nitrogen and having a hydroxyl group attached to each carbon except the carbon attached to the nitrogen, in an amount sufficient to inhibit deterioration of the fats and oils on storage.

17. Compositions comprising animal and vegetable fats and oils having incorporated therein 20 a salt of a long chain aliphatic acid and a mono N-aliphatic substituted amino alcohol in which

the alcohol radical is an open-chain radical containing at least 5 carbon atoms one carbon atom being singly bonded to the amino nitrogen and having a hydroxyl group attached to each carbon except the carbon attached to the nitrogen, in 5 an amount sufficient to inhibit deterioration of the fats and oils on storage.

18. Compositions comprising animal and vegetable fats and oils having incorporated therein 10 methylglucamine in an amount sufficient to inhibit deterioration of the fats and oils on storage.

19. Compositions comprising animal and vegetable fats and oils having incorporated therein 15 dodecylglucamine in an amount sufficient to inhibit deterioration of the fats and oils on storage.

20. Compositions comprising animal and vegetable fats and oils having incorporated therein 20 methylglucamine stearate in an amount sufficient to inhibit deterioration of the fats and oils on storage.
